DISPENSING TUBE CAP

John A. Mitchell, Santa Barbara, Calif.

Application September 5, 1933, Serial No. 688,216

10 Claims. (Cl. 221—60)

This invention relates to dispensing tubes or articles of like nature and particularly to a cap therefor and to the means for holding the cap in place upon the tube. Tubes of this nature which are used for paints, tooth paste and other pasty materials are ordinarily provided with a screw-threaded cap which screws on to the screw-threaded end of the tube. A cap of this character is very liable to be lost or at any rate 10 mislaid and one of the objects of my invention, therefore, is to provide a cap which is never separated from the tube itself.

A further object of the invention is to provide a cap which is rotatable upon an axis extending longitudinally of the tube so that it may be turned into or out of its closing position and a further object is to provide resilient means for urging said cap toward the orifice when the cap has been turned into its closing position.

20 Still a further object is to provide camming means acting as the cap is turned from its closing position to raise the cap from the surface of the discharge end of the tube and which will act to hold the cap in its closed position when the cap 25 is turned to cover the discharge orifice of the tube so that the cap cannot become accidentally displaced from its closing position but must be deliberately turned away from its closing position.

30 Other objects will appear in the course of the following description.

My invention is illustrated in the accompanying drawing, wherein:

Figure 1 is a fragmentary side elevation of the 35 upper end of the paste tube, the cap being in section;

Figure 2 is a front elevation of the paste tube, the cap being in section;

Figure 3 is a fragmentary sectional view of the 40 lower end of the cap showing the cam face thereon;

Figure 4 is the under side face view of the cap shown in Figure 1;

Figure 5 is a top plan view of the nozzle with 45 the cap removed;

Figure 6 is a fragmentary vertical sectional view through a modified form of cap, the upper end of the tube being shown in elevation;

Figure 7 is a top plan view of the nozzle 50 shown in Figure 6 with the top removed;

Figure 8 is a fragmentary side elevation of the upper end of the tube showing the cap in its closed position.

Referring to the drawing, 10 designates a compressible tube such as is used for paints, tooth

paste and the like. This tube terminates at its discharge end in an upwardly extending member 10 which has a flat top 11. This member may have any desired form but is shown as approximately rectangular in top plan view. This member 10 is provided with the discharge orifice 12 formed with a raised flange 13, the outer face of this flange being inclined outward and downward to the surface 11. Attached to the member 10 and extending upward therefrom is a 60 spindle 14, the upper end of which carries a spring. In Figure 1, this spring is shown as having a substantially straight upwardly extending portion 15 and then extending downward and outward beyond the shank as at 16 and having an 65 upwardly curved terminal portion 17.

The cap 18 is solid and has a length equal to the length of the portion 10. This cap is provided with a bore 19 which receives the spindle 14. The upper end of this bore is formed with an enlargement 20 providing an annularly extending shoulder 21 and above this enlargement 20, the bore is continued upward as at 22. It will be seen that when the cap is forced down tight upon the face 11 of the member 10, the spring will be received within the enlargement 20 and the free portion of the spring will spring outward as in Figure 1, the terminal end of the spring engaging against the end of the shoulder 21. The lower face of the cap immediately surrounding the bore 19 is formed with a cam surface 23 and the upper face of the member 10 immediately surrounding the spindle is also formed with a corresponding cam surface 24. These cam surfaces mate when the cap is either in the position parallel to the portion 10 and covering the opening 12 or when the cap 18 is at right angles to the portion 10, the cap being held with its cam surfaces in mating engagement with the cam surfaces 24 by the 80 spring 16.

In Figure 6 I illustrate another form of spring for the purpose of urging the cap downward against the face 11 of the portion 10 and in this case, the spring 25 is U-shaped in cross section and has outwardly turned terminal ends. The 100 spring 25 is held in place by the headed pin 26 which extends down into the spindle 14. The terminal ends of this spring 25 bear against the shoulder 21 of the enlargement 20 and the spring 25 yieldingly resists any upward movement of the 105 cap. It is obvious that the cap may be assembled upon the spindle 14 by simply forcing the cap downward on the spindle whereupon the bore 19 will force inward the ends of the spring 25 and then the ends of the spring 25 will spring outward 110

into applied position when the spring passes into the enlargement 20.

While I have illustrated in Figure 1 a certain form of cam, I do not wish to be limited to this as other forms of cam might be used. Thus in Figure 6 I have illustrated a cam constructed as follows. The upper face 11 of the member 10 is formed with a plurality of rounded bosses or protuberances 27 while the under face of the cap 10 is formed with corresponding cavities 28 which receive these protuberances when the cap 18 is parallel to the member 10. When the cap is turned, however, it rides up on these protuberances until the cap is turned at right angles to the member 10, whereupon the recesses 28 again receive these protuberances.

It will be seen that I have provided a dispensing tube with a cap which cannot become lost, which is easily turned into or out of closing position, which is so constructed that it cannot accidentally be turned from its closing position or to its closing position, and furthermore that I have provided a cap which, because of the relatively large flat sides, is capable of receiving ornamentation or initial letters so that the tube may be identified or trade-marked. Because of the fact that the cap is rectangular in cross section, a large area is provided for the application of fingers and thumb in turning the cap so that the cap may be readily snapped into its closing position or into its open position. The cap may be constructed from metal, bakelite, hard rubber or any plastic material and, of course, may be constructed of metal, if desired, or of any other suitable material.

It will be seen that the cam shoulders 23 and 24 or 27 and 28 assist in easing the top over the slight rim or flange 13 around the delivery opening and aid in holding the top detachably locked in its closing position or in its open position. The bottom face of the cap 18 is provided with a recess in which a body of cork, rubber, or other suitable material, is placed, as indicated at 13', to form a seal for contact with the flange 13. The spring pressure with which the cap is drawn downward tends to compress this seal over the end of the tube opening and thus prevents leakage or drying of the material contained within the tube.

While I have described two forms of my device, I do not wish to be limited to this as it is obvious that minor changes might be made therein without departing from the spirit of the invention as defined in the appended claims.

55 I claim:—

1. A dispensing tube having a nozzle at its discharge end formed with a flat upper surface and having a discharge orifice, there being an upwardly extending rim around the orifice, a cap pivoted upon the flat face of the nozzle for movement in the plane of said face toward or from the orifice, the cap having a recess on its under face mating with the rim, and a spring yieldingly holding the cap downward against the flat face of the nozzle.

2. A dispensing tube having a nozzle at its discharge end formed with a flat upper surface and having a discharge orifice, the mouth of the orifice having an upwardly extending rim, a cap pivoted upon the flat face of the nozzle for movement in the plane of said face, the pivotal connection permitting the cap to lift, and a spring urging the cap downward against the face of the nozzle, and coating means between the under face of the cap and the upper face of the nozzle

causing the lifting of the cap as it is turned away from the orifice.

3. A dispensing tube having a nozzle at its discharge end formed with a flat upper surface and having a discharge orifice, a cap pivoted upon the flat face of the nozzle for movement in the plane thereof toward or away from the orifice, a spring urging the cap downward against the face of the nozzle, and means automatically latching the cap in position over the orifice or in a position at right angles to the nozzle and turned away from the orifice.

4. A dispensing tube having a nozzle at its discharge end formed with a flat upper surface and having a discharge orifice, a spindle extending upward from the nozzle, a cap mounted upon said spindle for movement in the plane of the nozzle face and toward or away from the orifice, and a spring carried on the spindle and operatively engaging the cap and urging the cap downward.

5. A dispensing tube having a nozzle at its discharge end formed with a flat upper surface and having a discharge orifice, a spindle extending upward from the nozzle, a cap mounted upon said spindle for movement in the plane of the nozzle face and toward or away from the orifice, and a spring carried on the spindle and operatively engaging the cap and urging the cap downward, and cam means formed between the under face of the cap and the upper face of the nozzle acting to lift the cap from the face of the nozzle as the cap is turned, said cam means acting to detachably latch the cap in its closed position or its open position.

6. A dispensing tube having a nozzle at its discharge end formed with a flat upper surface and having a discharge orifice, a spindle extending upward from the flat face of the nozzle, a cap having a bore to receive the spindle, the bore at its inner end being formed with an annular enlargement forming an annular shoulder, and a resilient member mounted upon the upper end of the spindle and normally projecting laterally therefrom and yieldingly engaging against said annular shoulder to yieldingly resist upward movement of the cap.

7. A dispensing tube having a nozzle at its discharge end formed with a flat upper surface and having a discharge orifice, a spindle extending upward from the flat face of the nozzle, a cap having a bore to receive the spindle, the bore at its inner end being formed with an annular enlargement forming an annular shoulder, and a resilient member mounted upon the upper end of the spindle and normally projecting laterally therefrom and yieldingly engaging against said annular shoulder to yieldingly resist upward movement of the cap, the orifice having an upwardly projecting rim and the confronting faces of the nozzle and cap having cam elements mating when the cap is turned to a position closing the orifice or to a position unclosing the orifice, the cam members acting to lift the cap as the cap is rotated from its closing position.

8. A dispensing tube having a nozzle at its discharge end formed with a flat upper surface and having a discharge orifice therethrough, the orifice being formed with an upwardly projecting rim, a spindle extending upward from the upper face of the nozzle and spaced from the orifice, a spring mounted upon the upper end of the spindle and having a portion extending downward and outward beyond the spindle, and a cap having a bore to receive the spindle, the bore having an enlarged portion at its upper end providing an an-

nular shoulder with which the end of the spring engages, the spring thus swiveling the cap upon the spindle and yieldingly urging the cap downward, the confronting faces of the cap and nozzle concentric to the spindle being formed with coacting cam faces mating when the cap is in a position over the orifice or when it has been turned away from the orifice to a predetermined distance.

9. A dispensing tube having a nozzle at its discharge end, the nozzle being rectangular in plan and having a discharge orifice formed with an upwardly extending rim, and a cap rectangular in plan and rectangular in side elevation pivoted eccentrically with relation to the orifice in the nozzle, the under face of the cap having at one point a recess to receive the rim of the discharge orifice, the pivotal connection between the cap and nozzle permitting the movement of the cap

outward from the nozzle, and resilient means urging the cap downward against the face of the nozzle.

10. A paste dispensing tube having a nozzle at its discharge end, the nozzle having a flat upper surface and a discharge orifice surrounded by an inwardly and upwardly beveled rim, a cap pivoted upon the flat face of the nozzle for movement in the plane of said face from a position with the cap extending over the orifice to a position with the cap entirely uncovering said orifice, the cap having a recess on its under face adapted to receive the rim, and resilient means yieldingly urging the cap toward the flat face of the nozzle, said cap riding upward over the rim as the cap is turned into parallel relation to the nozzle and then springing down over the rim.
